United States Patent Office

Des. 187,377
Patented Mar. 8, 1960

187,377

PICTURE FRAME

Henry N. Hudes, Orange, N.J.

Application May 8, 1959, Serial No. 55,838

Term of patent 7 years

(Cl. D29—20)

FIG. 1

Fig. 1 is a plan view of a picture frame showing my new design; and

Fig. 2 is a side elevational view thereof, taken substantially along line 2—2 of Fig. 1 and drawn to an enlarged scale.

The dotted lines are for illustrative purposes only.

I claim:

The ornamental design for a picture frame, substantially as shown and described.
